US00D434683S

United States Patent [19]

Chang

[11] Patent Number: Des. 434,683

[45] Date of Patent: ** Dec. 5, 2000

[54] **INDUCTION TYPE ELECTRICAL MULTIMETER**

[75] Inventor: **Shang-Wen Chang**, Shin-Tien, Taiwan

[73] Assignee: **Appa Technology Corp.**, Taipei Hsien, Taiwan

[**] Term: **14 Years**

[21] Appl. No.: **29/114,992**

[22] Filed: **Dec. 7, 1999**

[51] LOC (7) Cl. **10-04**

[52] U.S. Cl. **D10/78**

[58] Field of Search .... D10/78, 79; 324/72.5, 324/110, 114, 115, 127, 149, 151 A, 151 R, 156, 158 F, 126; 336/175, 212

[57] **CLAIM**

The ornamental design for a induction type electrical multimeter, as shown and described.

DESCRIPTION

FIG. 1 is a perspective view of the induction type electrical multimeter showing the new design;

FIG. 2 is a front view of the induction type electrical multimeter;

FIG. 3 is a rear view of the induction type electrical multimeter;

FIG. 4 is a left side view of the induction type electrical multimeter;

FIG. 5 is a right side view of the induction type electrical multimeter;

FIG. 6 is a top view of the induction type electrical multimeter; and,

FIG. 7 is a bottom view of the induction type electrical multimeter.
